H. J. DE NAULT
RADIO RECEIVING PLATE
Filed May 15, 1924

FIG. 1.

FIG. 2.

FIG. 3.

Harry J. de Nault, INVENTOR.

BY

Frank A. Cutter, ATTORNEY.

UNITED STATES PATENT OFFICE

HARRY J. DE NAULT, OF SPRINGFIELD, MASSACHUSETTS.

RADIO-RECEIVING PLATE.

Application filed May 15, 1924. Serial No. 718,414.

To all whom it may concern:

Be it known that I, HARRY J. DE NAULT, a citizen of the United States of America, and a resident of Springfield, in the county 5 of Hampden and State of Massachusetts, have invented a new and useful Radio Receiving Plate, of which the following is a specification.

My invention relates to improvements in 10 the wireless or radio art, and more especially to improvements in the receiving branch of such art, and consists essentially of a radio-receiving plate made up of a bed of insulating material, which bed by preference is provided with a flange or rim that projects some distance above the top thereof, and an electrically-conducting member mounted on said bed, and provided with means for having connected therewith an 15 electrical conductor or wire, the plate thus constructed being of a size sufficient to receive thereon the base of the stand of a telephone desk-set, together with such other parts and members as may be necessary, or 20 desirable in order to render the plate complete and serviceable in every respect, all as hereinafter set forth.

The primary object of my invention is to provide means for utilizing telephone desk-sets, with their electric circuits, in place of 25 either outside or inside aerials, in connection with wireless-receiving outfits, such means consisting of a comparatively inexpensive, simple, convenient, strong, and durable radio- 30 receiving plate.

Another object is to produce such a plate which is adapted to receive thereon the base 35 of the stand of a telephone desk-set, and to hold the same safely and securely in place.

A further object is to provide a plate, of 40 the character described above, which is entirely safe to use, and does not in any way interfere with the ordinary operation of the telephone or injure the same.

With this plate no aerial is required other 45 than that furnished by the telephone wires leading to the desk-set stand which is placed on said plate.

Other objects and advantages will appear 50 in the course of the following description.

I attain the objects and secure the advantages of my invention by the means illustrated in the accompanying drawings, in which—

55 Figure 1 is a top view of a radio-receiving plate which embodies a practical form

of my invention; Fig. 2, a transverse section through said plate, taken on lines 2—2, looking in the direction of the associated arrow, in Fig. 1, and, Fig. 3, a side elevation 60 of the plate with a desk telephone-set or the stand thereof mounted on the plate, a portion of the plate being broken away to show the felt covering on the bottom and edge of the base of said stand. 65

Similar reference characters designate similar parts throughout the several views.

Although I have shown a round plate, and prefer that shape because the base of a telephone desk-set is round, so far as the 70 utility or the successful operation of the invention is concerned the plate might be of some other shape, hence I do not desire to be restricted in this particular.

As illustrated in the drawings, the radio-receiving plate comprises a bed 1 having a flange or rim 3 that extends above the top of said bed and clear around the same, a member 4 mounted on said bed inside of said rim, and having a lug or arm 5 which 75 extends outwardly through said rim beyond said bed. The bed 1 with its rim 3 is made of insulating material and preferably of wood, while the member 4 is made of electrically-conducting material and preferably 80 of copper. The member 4 may be secured to the bed 1 by means of a plurality of screws 6 which pass down through said member into said bed. The rim 3 extends above the member 4, and the space within 85 said rim is large enough to receive the base (as 7) of the stand (as 8) of a telephone desk-set.

A binding-post 9 is mounted on and secured to the arm 5, and a wire 10 is secured 90 to said binding-post. The wire 10 leads from a radio-receiving set (not shown), and would, in the absence of this plate, be connected with either an outside or inside aerial, where it is now connected with said 95 plate.

The bottom of the base 7 of the stand 8 is covered with a piece of felt 11 which extends upwardly around the edge of said base, but this felt frequently becomes worn 100 to such an extent that the metal of said base is exposed. I provide, therefore, a felt mat 12 to place over the conducting member 4 in the event the metal on the bottom or bottom edge of the base 7 becomes exposed. 110 The mat 12 is not necessary and will not ordinarily be used when the felt on the bot-

tom of the base of the telephone stand is intact. Should the metal of the base 7 come into contact with the conducting member 4, a short circuit would be produced and the telephone would be put out of operation, although the operation of the wireless-receiving set would not be interfered with.

The rim 3 assists materially in preventing the stand 8 from being pushed off of the plate, but such rim must be of insulating material, inasmuch as that part of the base 7 which is above the felt 11 may and frequently does come into contact with said rim, and then a short circuit would result if the rim were of metal.

At 13 and 14 are represented the telephone wires which are connected with the stand 8.

In practice, it is simply necessary to attach the wire 10 from the radio-receiving set to the binding-post 9, and place the base 7 of the stand 8 flat on the conducting member 4, the mat 12 being interposed if necessary. The radio-receiving set is now ready for use in the usual manner, and it is found that the operation of the same is materially enhanced by the use, with the aid or through the medium of my plate, of the telephone and telephone circuit in place of the aerial heretofore generally considered to be essential and necessary.

More or less change in the shape, size, construction and arrangement of some or all of the parts of this plate, in addition to those hereinbefore specifically pointed out, may be made without departing from the nature of my invention or exceeding the scope of what is claimed.

What I claim as my invention, and desire to secure by Letters Patent, is—

1. As an improved article of manufacture,

a radio-receiving plate comprising an insulating member provided with an insulating rim, a conducting member mounted on said insulating member, said rim extending above said conducting member, and the latter being adapted to have connected therewith a radio-receiving set conductor, and to have placed thereon within said rim a telephone desk-set stand, and means entirely to insulate said stand from said conducting member. 45

2. As an improved article of manufacture, a radio-receiving plate comprising an insulating member provided with an upwardly-extending rim, a conducting member mounted on said insulating member, and provided with an arm which extends through said rim beyond said insulating member for the purpose of having connected therewith a radio-receiving set conductor, said conducting member being adapted to have placed thereon within said rim a telephone desk-set stand, and means entirely to insulate said stand from said conducting member. 55 60

3. As an improved article of manufacture, a radio-receiving plate comprising an insulating member provided with a rim, a conducting member mounted on said insulating member, said rim extending above said conducting member, and the latter being adapted to have connected therewith a radio-receiving set conductor, and to have placed thereon within said rim a telephone desk-set stand, and an insulating mat receivable on said insulating member within 70 75 said rim, said stand being entirely insulated by said rim and mat from said conducting member.

HARRY J. DE NAULT.
